UNITED STATES PATENT OFFICE.

JESSIE SKINNER, OF LAMAR, COLORADO.

DESIGN FOR A DOLL.

Application filed April 30, 1925. Serial No. 13,269. Term of patent 7 years.

To all whom it may concern:

Be it known that I, JESSIE SKINNER, a citizen of the United States, residing at Lamar, in the county of Prowers and State of Colorado, have invented a new, original, and ornamental Design for a Doll, of which the following is a specification, reference being had to the accompanying drawing, forming part thereof.

The figure is a perspective view of a doll showing my new design.

What is claimed is:

The ornamental design for a doll, as shown.

JESSIE SKINNER.
